UNITED STATES PATENT OFFICE.

ALLAN A. GORDON, OF NORTH ATTLEBORO, MASSACHUSETTS, ASSIGNOR TO PAYE & BAKER MANUFACTURING CO., OF NORTH ATTLEBORO, MASSACHUSETTS.

DESIGN FOR A COMBINED SPOON AND FORK OR SIMILAR ARTICLE.

Application filed March 5, 1928. Serial No. 25,709. Term of patent 14 years.

To all whom it may concern:

Be it known that I, ALLAN A. GORDON, a citizen of the United States, residing at North Attleboro, in the county of Bristol, State of Massachusetts, have invented a new, original, and ornamental Design for a Combined Spoon and Fork or Similar Article, of which the following is a specification, reference being had to the accompanying drawing, forming part thereof.

Figure 1 is a top plan view of my invention; Fig. 2 is an edge elevation, and Fig. 3 is a bottom plan view of the device.

I claim:

The ornamental design for a combined spoon and fork or similar article, as shown.

ALLAN A. GORDON.
